Atty.

UNITED STATES PATENT OFFICE.

GEORGE P. WEIGEL, OF CLEVELAND, OHIO.

BOTTLE CAP.

Application filed February 23, 1923. Serial No. 620,756.

To all whom it may concern:

Be it known that I, GEORGE P. WEIGEL, a citizen of the United States, residing at Cleveland, in the county of Cuyahoga and State of Ohio, have invented certain new and useful Improvements in Bottle Caps, of which the following is a specification.

This invention relates to bottle caps, and has for its object to provide a combined 10 bottle cap and stopper especially adapted and intended for temporary use on milk bottles, to close the bottle after the ordinary paper cap or stopper is removed. The present device can be changed from one bottle to another 15 so as to exclude dust and dirt from the bottle in use. It will preferably be made of glass so that it can easily be kept clean.

The device is illustrated in the accompanying drawings in which Fig. 1 is a section of 20 the cap as applied to a bottle mouth. Fig. 2 is an inside plan of the cap.

In the drawings, an ordinary milk bottle is indicated at 6, having a shoulder at 7 which receives the usual paper stopper. Upon 25 removal of the stopper, the present device is applied to the bottle. It comprises a cap having on its under side an annular or circular stopper section 8, which may be made hollow as shown, for the sake of lightness, and this 30 stopper extension is of proper size to fit within the mouth of the bottle, and on its outer side it is provided with a shoulder 9 extending around the same of proper size and in proper position to seat against the shoulder 7 on the 35 bottle when the cap is applied. The outer part or rim of the cap extends outwardly a sufficient distance to cover the top of the bottle neck, as shown at 10, and the extreme

edge fits around or against the outer side of the lip of the bottle, as shown at 11. Or, 40 stated in another way, the under side of the rim of the cap is grooved to receive the circular lip around the mouth of the bottle.

A cap as constructed will fit closely and snugly to the bottle mouth and will remain 45 in place without slipping, during ordinary movement of the bottle. It will exclude dirt from the bottle, and can be readily changed from one bottle to another as occasion may demand. 50

The particular form of the cap may be changed to accommodate it to bottles of different standard types.

I claim:

A combined bottle cap and stopper, made 55 of glass, and adapted for interchangeable use on milk bottles or the like, said cap having a smooth unbroken upper surface and having on its under side a downwardly extending central stopper section provided with 60 a shoulder to rest on a shoulder in the bottle neck, the rim of the cap projecting outwardly and being curved downwardly to fit against the outer side of the top of the bottle neck, said rim terminating at substantially the line 65 of greatest diameter of said top and spaced laterally therefrom, whereby said cap is capable of removal without distortion and is interchangeable from one bottle to another.

In testimony whereof, I affix my signature 70 in presence of two witnesses.

GEORGE P. WEIGEL.

Witnesses:

JOHN A. BOMMHARDT,
EDWARD J. HOBDAY.
